UNITED STATES PATENT OFFICE.

OTTO ARAM, OF PHILADELPHIA, PENNSYLVANIA, ASSIGNOR TO WESTINGHOUSE ELECTRIC AND MANUFACTURING COMPANY, A CORPORATION OF PENNSYLVANIA.

AGITATOR GRATE FOR UNDERFEED STOKERS.

Application filed June 4, 1923. Serial No. 643,368.

To all whom it may concern:

Be it known that I, OTTO ARAM, a citizen of the United States, and a resident of Philadelphia, in the county of Philadelphia and 5 State of Pennsylvania, have invented a new and useful Improvement in Agitator Grates for Underfeed Stokers, of which the following is a specification.

My invention relates to stoker furnaces, 10 more particularly to stoker furnaces having an underfeed grate followed by an overfeed grate, and it has for an object to provide in an apparatus of the character designated an overfeed grate construction which shall 15 maintain the partially consumed fuel passing thereover in a relatively fine and loose condition. A further object is to provide in conjunction with an underfeed grate an overfeed grate having a plurality of oscillating grate sections so constructed and arranged that a vigorous agitation of the fuel thereon is obtained and the sifting of fuel and ash between the grates and between the sections of the overfeed grate is practically 20 inhibited. A still further object of my invention is to provide in an overfeed grate having a plurality of oscillating grate sections a simple and efficient arrangement for oscillating the several grate sections.

These and other objects of my invention, 25 which are made more manifest in the following description, may be attained by means of the apparatus illustrated in the accompanying drawing, in which Fig. 1 is a view in longitudinal section through a stoker embodying my invention; and Fig. 2 is a plan view of the stoker illustrated in Fig. 1.

It has heretofore been proposed to utilize 30 in stoker furnaces an overfeed grate receiving the residuum of fuel from the underfeed grate for the purpose of more completely burning out the combustible content of the residuum discharged from the underfeed 35 grate. In the installations commonly employed, the residuum frequently agglomerates in large masses, particularly where fuels of low fusibility are employed, which masses occlude the combustible portion of the residuum and prevent the burning thereof. I 40 have found that if the refuse discharge from the underfeed grate is given a more vigorous and prolonged agitation in passing over the underfeed grate than is now customary, the 45 residuum of the fuel will have a lesser tend-

ency to agglomerate in large masses and such clinker masses as do form will be broken up by the vigorous agitation, permitting a freer access of air to the combustible content of the residuum, and hence 50 a more complete combustion of the fuel fed to the furnace. I have been able to secure a requisite agitation of the fuel by means of a plurality of oscillating grate sections, associated one with the other to oscillate in 55 unison, the grate sections providing a downwardly inclined fuel supporting surface of more than usual length in the direction of travel of the fuel.

Referring to the drawing for a more detailed description of my invention, I show at 10 an underfeed grate delivering partially consumed fuel to an overfeed grate 11, from whence the refuse passes to a dump grate 12 for discharge to an ash pit 13.

As shown, the underfeed grate 10 is composed of alternating retorts 15 and tuyère banks 16. The retorts are defined at the sides by wall members 17 supported upon end castings 18 and 19, which in turn are carried by I-beams 20 and 21, respectively, and at the bottom by deflecting plates 23, bottom plates 24 and retort tuyères 25. The tuyère banks 16 consist of a plurality of tuyère blocks 28 carried by the retort wall members 17 and superimposed one upon another in stepped relation. A ram box 30 is provided for each retort, in which a reciprocating ram 31 is disposed in the usual manner. A hopper 32 is arranged to supply 50 fuel to the several ram boxes 30, as is the common practice in the construction of apparatus of this character.

The above arrangement is conventional and forms per se no part of the present invention, it being understood that various forms of underfeed grate may be employed in carrying out the present invention in lieu of that above described and illustrated in the drawings.

The overfeed grate 11 includes forward oscillating grate sections 40 and rear oscillating grate sections 41. The grate sections 40 are disposed contiguous to the retort end member 19 of the underfeed grate 10, and are pivotally mounted at their forward ends for oscillation upon a shaft 42. The shaft 42 may be journaled in the side walls of the furnace in bearings 43. As shown, the 55 grate sections 40 are hollow and provided 60

with inlet ports 44 which cooperate with ports 45 in the member 19 to deliver air to the interior of the grate sections 40. Ports 46 in the upper surface of the grate sections 40 are provided for the delivery of air to the fuel bed thereon.

The rear oscillating grate sections 41 are centrally supported upon a shaft 50 journaled in the side walls of the furnace in bearing 51. The grate sections 41 have portions 53 extending forwardly from the shaft 51 upon which the rear end portions of the grate sections 40 are supported. Rearwardly extending portions 54 of the grate sections 41 terminate in arcuate depending flanges 55. Each of the grate sections 41 is also provided with ports 56 for the delivery of air to the fuel resting thereon.

The grate sections 41 may be oscillated by any suitable mechanism. As shown, a reciprocating engine 60 of conventional construction acts through a connecting rod 61 and a crank arm 62 secured to the shaft 50 for effecting the desired oscillatory movement of the grate sections 41.

Air is supplied to an air chamber 70 of the underfeed grate 10 through a duct 71 and is distributed to the tuyères 28 in the usual manner. A branch duct 72, controlled by a damper 73, leads from the chamber 70 to an auxiliary air chamber 74 disposed beneath the overfeed grate 11. Air from the chamber 74 passes through the ports 56 of the grate sections 41 to the fuel bed thereon.

As shown in the drawing, air for the grate sections 40 is taken from the chamber 70 through the cooperating ports 44 and 45. It is to be understood, however, that the grate sections 40 may be open to the chamber 74 and receive air therefrom instead of from the chamber 70. In order to prevent an undue leakage of air at the rear edge of the grate sections 41, the rear wall of the chamber 74 is made to conform in shape to the arcuate flanges 55 of the grate sections 41 and is closely spaced therefrom as shown at 76. A sealing means may also be employed between the walls 76 and the flanges 55, if desired.

The dump grate 12 is of conventional construction and as shown, is hollow for the reception of air and is mounted upon channel irons 80 in the furnace bridge wall, which irons serve as an air duct to supply air through the cooperating ports 81 and 82 to the interior of the dump grate 12, from whence the air is delivered to the refuse upon the dump grate through ports 83. The dump grate is pivoted to swing near its rear edge upon a shaft 84, as is common with constructions of this character.

The mode of operation of a stoker furnace constructed as above described is briefly as follows: Fuel from the hopper 32 is fed into the retorts 15 and over the tuyère banks

16 by means of the rams 31. The fuel passes over the underfeed grate and is largely consumed thereon. The residuum of the fuel is delivered to the overfeed grate in a highly heated condition conducive to agglomeration, or the formation of clinker masses. The residuum of the fuel at this point, however, contains a considerable portion of combustible and it is essential, if this combustible is to be made available for the generation of heat, that the residuum be maintained in a relatively fine and loose condition in order that air delivered to this residuum of the fuel upon the overfeed grate may have access to the combustible matter therein. This result is effected with a high degree of efficiency by causing an oscillatory movement of the grate sections 40 and 41. The oscillatory movement is imparted directly to the grate sections 41 by the engine 60, and to the grate sections 40 by means of the overlapping relation of the grate sections 40 and 41, the rear ends of the grate sections 40 rising and falling with the forward ends of the grate sections 41. The length of the path of travel of the residuum over the overfeed grate 11 and the thorough agitation of the residuum during its travel thereover insure a complete burning of the combustible content therefrom. The clinker and ash, practically free of combustible matter, are periodically discharged to the pit 13 by means of the dump grate 12.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a stoker, the combination with an underfeed grate, of an inclined overfeed grate receiving fuel therefrom and comprising two oscillating grate sections, the forward grate section being pivoted at its forward end and the rear grate section being pivoted at a central portion, said grate sections being so associated that the oscillation of the rear grate section also effects an oscillation of the forward grate section, and means for oscillating the rear grate section.

2. In a stoker, the combination with an underfeed grate, of an inclined overfeed grate receiving fuel therefrom and comprising two oscillating grate sections, the forward grate section being pivoted at its forward end and the rear grate section being pivoted at a central portion, the forward grate section overlapping the rear grate section in all positions of oscillations, whereby sifting of fuel therebetween is minimized, said grate sections being so associated that

the oscillation of the rear grate section also effects an oscillation of the forward grate section, and means for oscillating the rear grate section.

- 5 3. In a stoker, the combination with an underfeed grate, of an inclined overfeed grate receiving fuel therefrom and comprising two oscillating grate sections, the forward grate section being pivoted at its for-

ward end and the rear grate section being

pivoted at a central portion, the forward grate section overlapping and being supported by the forward end of the rear grate section in all positions of oscillation and means for oscillating the rear grate section. 15

In testimony whereof, I have hereunto subscribed my name this 24th day of May, 1923.

OTTO ARAM.
